PRODUCTION OF SULPHONATION DERIVATIVES

Wendell W. Moyer, Decatur, Ill., assignor to
The Solvay Process Company, New York, N. Y.,
a corporation of New York

No Drawing. Application September 12, 1938,
Serial No. 229,534

10 Claims. (Cl. 260—400)

The present invention relates to a process for the preparation of sulphonation derivatives containing saturated higher fatty acid radicals, which derivatives are valuable as detergents and wetting, emulsifying, and the like agents.

An object of the invention is to provide a process for the production of sulphonation products comprising a mixture of alpha-sulphonic acid derivatives of saturated higher fatty acids and sulphur trioxide used in the reaction. Further, the best results are obtained if the reaction is carried out under substantially anhydrous conditions; i. e., under conditions such that there is present in the reaction mixture not more than one per cent of water based on the weight of sulphur trioxide used.

Another object of the invention is to provide a process for the production of products comprising essentially alpha-sulphonic acid derivatives of saturated higher fatty acids which may be carried out efficiently on a commercial scale.

Other objects of the invention will in part be obvious and will in part appear hereinafter.

It has been discovered in accordance with the present invention that by sulphonating amides of saturated higher fatty acids with sulphur trioxide in the presence of liquid sulphur dioxide valuable products are obtained which contain an important amount of alpha-sulphonic acid derivatives of saturated higher fatty acids rather than products which consist only of the sulphonation derivatives of the amides themselves, as might be expected. In carrying out the sulphonation of these amides, it has been found to be important if products of good quality are to be obtained that the saturated higher fatty acid amide or mixture of amides used as the starting material should not contain an excessive amount of amides of unsaturated higher fatty acids. For example, it has been found that the amides of saturated higher fatty acids used as the starting materials in the process should be free from more than five per cent, and especially two per cent, by weight of amides of unsaturated higher fatty acids.

It has also been found to be important to control the amount of water present in the sulphonation reaction mixture. Thus, it has been found that as the water present in the reaction mixture is increased, there is a corresponding decrease in the yields of the desired products. Further, while in the use of a reaction mixture containing a material amount of water, the yields may be improved by increasing the vigor of the sulphonating conditions, such as the temperatures, this is not satisfactory because the products obtained are of inferior color, indicating a relatively large amount of impurities therein.

The color of these products is inferior to the color of products obtainable in the same yields by a process involving the use of a reaction mixture containing a smaller proportion of water. It has been found that the sulphonation reaction should be carried out under conditions such that there is present in the mixture not more than three per cent of water based on the weight of sulphur trioxide used in the reaction. Further, the best results are obtained if the reaction is carried out under substantially anhydrous conditions; i. e., under conditions such that there is present in the reaction mixture not more than one per cent of water based on the weight of sulphur trioxide used.

It is surprising that this process is productive of the results noted since the usual sulphonating procedures, if applied to the sulphonation of amides of saturated higher fatty acids, are unsatisfactory because they result in the production of dark-colored products or in a small degree of sulphonation. Thus, if oleum, concentrated sulphuric acid, or chlorsulphonic acid is used in the sulphonation, significant yields of sulphonation products are not obtained at low temperatures, while at high temperatures serious carbonization of the organic material occurs. It appears that the results obtained with oleum and sulphuric acid are due to the fact that these agents contain combined water which is deleterious. Chlorsulphonic acid is undesirable for the further reason that hydrochloric acid is formed which must be removed.

The products of the present process, which are preferably employed in the salt form, in general consist of mixtures of alpha-sulphonic acid derivatives of the saturated higher fatty acids whose amides have been used as the starting materials in the process, alpha-sulphonic acid derivatives of the amides themselves, and other nitrogen-containing alpha-sulphonic acid derivatives of saturated higher fatty acid compounds which are believed to be sulphonamides. These products as such, or in admixture with salts such as, for example, sodium sulphate or ammonium sulphate, are valuable detergent, wetting, emulsifying, and the like agents which are active in hard water and in acid and alkaline solutions. Thus, as compared with ordinary soaps they are not hydrolyzed to the free unsaponified fatty acids in acid solutions. Also, they do not have the disadvantage of soaps of being precipitated in the form of sticky curds from solutions containing calcium or magnesium salts which have no detergent value but which

constitute impurities. As compared with ordinary sulphonated fatty acids obtained by the sulphonation of unsaturated and/or hydroxy fatty acids, of which Turkey red oils are outstanding examples, the products possess considerably superior wetting and detergent properties and are more stable against hydrolysis. The properties of the products, as compared with the properties of ordinary sulphonated fatty acids, appear to be due to the facts that the sulphonic acid group in the derivatives in the products is at the end of a long carbon chain, and they contain a sulphonic acid group rather than the more easily hydrolyzed sulphuric acid ester group.

18 The starting material employed in the present process may be an amide of any saturated higher fatty acid or a mixture of such amides. In this connection it should be understood that the term "saturated higher fatty acid" is employed herein to denote any saturated fatty acid which contains at least 8 carbon atoms and which is free from hydroxyl groups. The more valuable products are obtained in accordance with the present invention by sulphonating amides of saturated higher fatty acids which contain from 8 to 24, and especially from 14 to 18, carbon atoms. Examples of such fatty acids are the following: myristic acid, palmitic acid, stearic acid, arachidic acid, behenic acid, and lignoceric acid.

30 The process is preferably carried out using amides of saturated higher fatty acids derived from naturally occurring fats or oils of which tallow, cocoanut oil, babassu oil, palm oil, and fish oils; e. g., menhaden fish oil, are examples, as starting materials. The naturally occurring fats or oils may be used as the initial starting materials in the process. In this case it is advisable to subject them to hydrogenation as the first 40 step in the process. As is well known, the naturally occurring fats and oils are composed of glycerides of unsaturated as well as saturated higher fatty acids: tallow, for example, contains glycerides of the saturated fatty acids, stearic acid, palmitic acid, and myristic acid; and glycerides of the unsaturated fatty acids, oleic acid, and linoleic acid. The hydrogenation of a fat or oil is preferably effected by contacting the material with hydrogen at an elevated temperature and at a superatmospheric pressure in the presence of a hydrogenation catalyst, such as nickel. The product obtained as a result of this treatment is composed substantially entirely of glycerides of saturated fatty acids.

55 Amides adapted for use in the present process can be obtained from a hydrogenated fat or oil by first hydrolyzing the fat or oil to the free acids and glycerine and then, after removing the glycerine, amidating the free acids with ammonia. The amides can also be prepared from the hydrogenated fat or oil directly by subjecting the fat or oil to ammonolysis in any convenient or desired manner, several of which are well known in the art. The amides formed in this way can be easily separated from the remainder of the reaction mixture by distillation under vacuum.

70 The amides prepared by ammonolysis of a hydrogenated fat or oil or in any other suitable manner are sulphonated in accordance with the present invention by bringing them into reactive contact with sulphur trioxide in the presence of liquid sulphur dioxide as the solvent medium. This is preferably carried out by dissolving and/or suspending the amides in liquid

sulphur dioxide, and then introducing sulphur trioxide, which is conveniently in solution in liquid sulphur dioxide, into the resulting solution or suspension. At the completion of the sulphonation, the sulphonation derivatives are recovered from the remainder of the reaction mixture as such, or in admixture with sulphates. For example, the liquid sulphur dioxide may be distilled off and condensed for use in a succeeding run of the process.

10 When the process is operated by removing the bulk of the liquid sulphur dioxide by distillation, the mixture remaining is treated so as to convert the sulphonation derivatives, which are present in the free acid form, to the salt form. 15 This is conveniently accomplished by introducing the mixture into water, and then neutralizing the resulting aqueous mixture with a suitable alkaline material; e. g., with sodium hydroxide. The neutralizing agent may be added in 20 such proportions as to form predominantly partial salts of the sulphonation derivatives or in such proportions as to form the wholly neutralized salts. If the neutralization is conducted so as to form the partial salts, these may be recovered by precipitating them from the mixture and filtering off the precipitate, since the remainder of the mixture possesses greater water-solubility than the partial salts. On the other hand, the partially neutralized aqueous mixture 30 may be dried whereby there is obtained a dry product consisting of the partial salts of the sulphonation derivatives in admixture with sulphates formed by reaction between the alkaline neutralizing agent and sulphuric acid formed in 35 the reaction, and between ammonia released in the reaction and the sulphuric acid. If the neutralization has been carried out so as to form the wholly neutralized salts of the sulphonation derivatives, the neutralized mixture is preferably 40 dried, as by means of a spray or rotary drum drier, whereby there is obtained a dry product similar to that described above except that it contains the wholly neutralized, rather than the partially neutralized, salts of the derivatives. 45

As before indicated, the products of the present invention ordinarily are mixtures of the salts of alpha-sulphonic acid derivatives of saturated higher fatty acids, alpha-sulphonic acid derivatives of saturated higher fatty acid amides, and alpha-sulphonic acid derivatives of nitrogen-containing saturated higher fatty acid compounds which are believed to be sulphonamides. This mixed product is a valuable product and for most purposes is at least as valuable as a product in which the essential detergent ingredient is the alpha-sulphonic acid derivative of a saturated higher fatty acid. For certain purposes, however, it may be found of advantage to convert it to a product which is substantially free 55 from sulphonated amides or other nitrogen-containing sulphonation derivatives. As a feature of the invention it has been found that this may be accomplished in a simple manner by subjecting the product to a hydrolysis treatment with an acid such as, for example, hydrochloric acid. The hydrolyzed product on neutralization with a suitable alkaline material, such as sodium hydroxide, consists essentially of salts of alpha-sulphonic acid derivatives of saturated higher 60 fatty acids, sulphates, and salts of the acid employed in the hydrolysis reaction.

70 The salts present in the products appear to improve the valuable properties of the products. If desired, salts (in addition to those formed in 75

the reaction) such as, for example, sodium sulphate, ammonium sulphate, monosodium phosphate, disodium phosphate, borax, sodium silicate, and sodium sesquicarbonate, can be added to the products. Also, in certain cases it may be found of advantage to combine the dry products with other detergents and/or wetting agents, such as ordinary soaps and other sulphonated products.

10 In order that the invention may be more fully understood, reference should be had to the following specific examples in which are disclosed processes coming within the scope of the present invention. It will be understood that these examples are given for illustrative purposes merely and are not intended as limitations of the invention. The parts are by weight and the temperatures are in degrees centigrade.

Example 1.—100 parts of saturated higher fatty acid amides having an average carbon content of 17 to 18 atoms per molecule and containing less than two per cent by weight of amides of unsaturated higher fatty acids, are dissolved and/or suspended in substantially anhydrous liquid sulphur dioxide in a suitable vessel capable of withstanding moderate pressures. A mixture containing one mol of sulphur trioxide and 50 to 70 mols of anhydrous liquid sulphur dioxide is added continuously with vigorous stirring over a period of about two hours; the rate of introduction of the solution of sulphur trioxide and sulphur dioxide being such that about three mols of sulphur trioxide are introduced for each mol of the saturated higher fatty acid amides contained in the reaction mixture. The temperature of the reaction mixture is controlled during the addition so as to lie within the range of 30° to 40° and the reaction is permitted to continue for an additional two hours at said temperature. In order to avoid loss of sulphur dioxide and to assure satisfactory progress of the reaction, the pressure is maintained at about the vapor pressure of sulphur dioxide at the existing temperature. At the completion of the sulphonation, which will require about four hours under these conditions, substantially all of the sulphur dioxide is vaporized from the reaction mass, condensed in a receiver, and stored for use in a succeeding run of the process. The mass remaining after the removal of the bulk of the sulphur dioxide is dissolved in a minimum quantity of water and the resulting aqueous mixture is heated to remove residual sulphur dioxide. The aqueous mixture obtained in this way is then neutralized to a pH of 7 with an aqueous caustic soda solution. The mixture after neutralization is in the form of a slurry containing the sodium salts of the sulphonation derivatives present therein. This slurry is dried as by means of a spray or rotary drum drier to form a dry product which has valuable detergent, wetting, emulsifying, and the like properties.

Example 2.—4.54 parts of myristamide are mixed with 9.6 parts of sulphur trioxide in about 143 parts of liquid sulphur dioxide in a vessel provided with a sealing means. The vessel is then sealed and is maintained at room temperature for about 24 hours. The vessel is then opened, the sulphur dioxide is distilled off, and the residue is introduced into water and treated for the preparation of a detergent product. For example, the aqueous mixture can be neutralized and further treated as described in Example 1.

When proceeding in accordance with the general procedure of the above examples it will be

understood that additional salts may be added during the neutralization and drying procedures (e. g., up to 20 to 50 per cent by weight of the sulphonated compound), or, if desired, an excess of sulphur trioxide over that required in the sulphonation may be used and neutralized with an alkaline material (e. g., a caustic alkali or ammonia) to form in situ a salt constituting a filler.

It will be understood, of course, that the starting materials employed in the examples may be replaced by amides of other saturated higher fatty acids; e. g., any of those referred to above. Further, while it is preferred to employ as the starting materials in the present process amides which are unsubstituted in the amino groups, it is possible to employ amides which contain as N-substituents low molecular aliphatic radicals free from reactive substituents. As examples of amines whose amides are of interest in this connection, the following may be mentioned by way of example: methyl amine, dimethyl amine, ethyl amine, diethyl amine, methyl ethyl amine, and methoxyethyl methyl amine.

In place of the neutralizing agents used in the examples, there may be used any other alkaline material capable of reacting with a sulphonate group. Thus, sodium carbonate, potassium carbonate, potassium hydroxide, ammonia, and methyl amine, can be used for this purpose.

The amount of sulphur trioxide employed in the process can be varied within relatively wide limits but in order to produce satisfactory yields of the desired products, it should not be reduced below 2.5 mols for each mol of the saturated amide or amides subjected to treatment. On the other hand, it is ordinarily unnecessary to employ more than 4 mols of sulphur trioxide per mol of amide. For most efficient operation it is preferable to employ from 3 to 3.5 mols of sulphur trioxide for each mol of the saturated fatty acid amide. An excess of sulphur trioxide ordinarily does not have a critical effect on the operativeness of the process, and in some cases where it is desired to form a sulphate in situ, it is of advantage. With respect to the amount of liquid sulphur dioxide required as the solvent medium it will be understood that this amount is dependent in large measure upon the solubility in this medium of the particular saturated fatty acid amide or mixture of amides used as the starting material in the process. A relatively large amount of liquid sulphur dioxide may be used in the reaction without materially adding to the cost of the process since the sulphur dioxide may be efficiently recovered for reuse in a succeeding run of the process by distillation and condensation.

The sulphonation reaction can be carried out at ordinary temperatures and because of simplicity of operation such temperatures are usually employed. If desired, however, a higher or lower temperature can be used, for example, temperatures varying from 20° to 50° C. are suitable. The time required for the sulphonation reaction is also a variable factor, being dependent upon the specific saturated fatty acid amide or amides subjected to treatment, the apparatus employed, the temperature, and other conditions. Under ordinary conditions of operation, a reaction period of from 3 to 20 hours is sufficient to complete the sulphonation.

In the appended claims where the term "an amide of a saturated higher fatty acid" is referred to it will be understood that it is intended

to include mixtures of such amides as well as single amides.

Since certain changes may be made in the above process without departing from the scope 5 of the invention, the above description should be interpreted as illustrative and not in a limiting sense.

I claim:

1. The process for the preparation of alpha-10 sulphonic acid derivatives of saturated higher fatty acids which comprises sulphonating an amide of a saturated higher fatty acid with sulphur trioxide in the presence of liquid sulphur dioxide.

2. The process for the preparation of alpha-15 sulphonic acid derivatives of saturated higher fatty acids which comprises sulphonating an amide of a saturated higher fatty acid containing 8 to 24 carbon atoms and containing not substantially more than five per cent of amides 20 of unsaturated higher fatty acids with sulphur trioxide in the presence of liquid sulphur dioxide.

3. The process for the preparation of alpha-25 sulphonic acid derivatives of saturated higher fatty acids which comprises sulphonating an amide of a saturated higher fatty acid containing 8 to 24 carbon atoms and containing not substantially more than five per cent of amides of unsaturated higher fatty acids with sulphur trioxide in a reaction mixture in which liquid sulphur dioxide is the solvent medium, said reaction mixture being free from more than three 30 per cent of water based on the weight of sulphur trioxide used.

4. The process for the preparation of alpha-35 sulphonic acid derivatives of saturated higher fatty acids, which comprises sulphonating an amide of a saturated higher fatty acid containing not substantially more than five per cent of amides of unsaturated higher fatty acids with 40 2.5 to 4 mols of sulphur trioxide for each mol of said amide of a saturated higher fatty acid in the presence of liquid sulphur dioxide under substantially anhydrous conditions.

5. The process for the preparation of the alpha-45 sulphonic acid derivative of myristic acid which comprises sulphonating myristamide containing not substantially more than five per cent of amides of unsaturated higher fatty acids with sulphur trioxide in the presence of liquid sulphur dioxide under substantially anhydrous conditions.

6. The process for the preparation of alpha-55 sulphonic acid derivatives of saturated higher fatty acids which comprises sulphonating an amide of a saturated higher fatty acid containing not substantially more than five per cent of amides of unsaturated higher fatty acids with 60 2.5 to 4 mols of sulphur trioxide in the presence of liquid sulphur dioxide under substantially anhydrous conditions at a temperature of 20° to 50° C. for 3 to 20 hours.

7. The process for the preparation of a detergent product comprising alpha-sulphonic acid derivatives of saturated higher fatty acids and alpha-sulphonic acid derivatives of amides of saturated higher fatty acids which comprises 5 sulphonating an amide of a saturated higher fatty acid containing not substantially more than five per cent of amides of unsaturated higher fatty acids with sulphur trioxide under substantially anhydrous conditions in a reaction mixture in which liquid sulphur dioxide is the solvent medium, distilling off sulphur dioxide from the reaction mixture, mixing the remainder of the reaction mixture with water, neutralizing the resulting aqueous mixture, and drying the neutralized mixture. 10

8. The process for the preparation of a detergent product comprising alpha-sulphonic acid derivatives of saturated higher fatty acids and alpha-sulphonic acid derivatives of amides of 20 saturated higher fatty acids which comprises forming a substantially anhydrous reaction mixture comprising one mol of an amide of a saturated higher fatty acid containing not substantially more than two per cent of amides of 25 unsaturated higher fatty acids and 3 to 3.5 mols of sulphur trioxide in a solvent medium composed substantially of liquid sulphur dioxide, maintaining the reaction mixture at a temperature of 20° to 50° C. for 3 to 20 hours, whereby 30 there are formed in the reaction mixture sulphonation derivatives comprising the alpha-sulphonic acid derivative of the saturated higher fatty acid corresponding to said amide of a saturated higher fatty acid and the alpha-sulphonic acid derivative of said amide, separating the sulphonation derivatives from the liquid sulphur dioxide, and neutralizing the sulphonation derivatives. 35

9. The process for the preparation of alpha-40 sulphonic acid derivatives of saturated higher fatty acids which comprises sulphonating an amide of a saturated higher fatty acid containing 45 8 to 24 carbon atoms and containing not substantially more than five per cent of amides of unsaturated higher fatty acids with sulphur trioxide in the presence of liquid sulphur dioxide, whereby a mixed sulphonation product containing nitrogen is produced, and hydrolyzing said mixed sulphonation product to remove nitrogen 50 therefrom.

10. The process for the preparation of alpha-55 sulphonic acid derivatives of saturated higher fatty acids which comprises sulphonating an amide of a saturated higher fatty acid containing not substantially more than five per cent of amides of unsaturated higher fatty acids with sulphur trioxide in a reaction mixture in which liquid sulphur dioxide is the solvent medium. 60

WENDELL W. MOYER. 60
